UNITED STATES PATENT OFFICE.

BION B. FARNHAM, OF NIAGARA FALLS, NEW YORK.

SUCTION-BOX.

No. 839,279.

Specification of Letters Patent.

Patented Dec. 25, 1906.

Application filed September 4, 1906. Serial No. 333,197.

To all whom it may concern:

Be it known that I, BION B. FARNHAM, a citizen of the United States, residing at Niagara Falls, in the county of Niagara and State of New York, have invented a new and useful Suction-Box, of which the following is a specification.

This invention relates to suction-boxes or rolls such as are used particularly in connection with paper-making machinery.

The objects of the invention are to improve and simplify the construction of such devices; furthermore, to increase their efficiency in operation and to decrease the expense attending their manufacture.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of the following claims without departing from the spirit of the invention or sacrificing any of its advantages.

In the accompanying drawings, forming part of this specification, Figure 1 is a longitudinal section on the line 1 1 of Fig. 5, partly in elevation, showing one end of a suction-box constructed in accordance with the invention. Fig. 2 is a similar view on the line 2 2 of Fig. 5. Fig. 3 is a detail view of the rack-and-pinion mechanism for moving the regulating devices of the suction-box. Fig. 4 is a side elevation, partly broken away, of a suction-box constructed in accordance with the invention. Fig. 5 is an end elevation, partly in section. Fig. 6 is a view in elevation looking at the inner side of one of the end plates, and Fig. 7 is a perspective view of one of the adjustable cut-off plates.

Like reference-numerals indicate corresponding parts in the different figures of the drawings.

The improved suction-box of the present invention consists of a cylindrical body portion or roll 1, which is formed around its periphery with a plurality of longitudinally-extending suction-passages 2, which are open at both ends and are of any suitable shape in cross-section. Each of the suction-passages 2 is formed with a plurality of radially-extending inlets 3, which are tapered inwardly from the periphery of the roll, as shown in Fig. 1. The roll 1 preferably is wrapped

with wire 4, as shown in Fig. 4. It will be understood that when suction is exerted upon the suction-passages 2, as will herein-after appear, air is drawn inward through the inlets 3 and also through the web of paper which covers said inlets. For the purpose of shutting off or closing some of the inlets 3 at the two ends of each suction-passage 2 when the machinery is operating upon a narrow web of paper or when for any other reason it becomes desirable that only the inlets 3 adjacent the central portion of the roll shall be open, each of the suction-passages 2 is provided with a stationary metallic lining 5, through which extend some of the inlets 3, as shown in Fig. 1. Mounted for longitudinal sliding movement in each metallic lining 5 is a sleeve 6, which when it is moved toward the middle of the roll is adapted to cover and close some of the inlets 3. It will be understood that the arrangement of the lining 5 and sleeve 6 shown in Fig. 1 is duplicated at the opposite end of the roll or suction-box. The means for simultaneously adjusting the sleeves 6 of the different suction-passages toward or from the middle of the roll preferably consist of a rod 7, which is journaled at each end in a bearing-box 8, supported in the center of the lining 5 by means of suitable radial arms 9. The rod 7 is formed at one end with a set of threads 10 and at its opposite end with a similar set of threads extending in the reverse direction in an old and well-known manner. The threads 10 extend through a threaded member 11, held securely in the center of each of the sleeves 6 by means of radial arms 12. It will be obvious that when the rod 7 is rotated in one direction the sleeves 6 at the opposite ends of each suction-passage 2 will be moved toward each other to close some of the inlets 3 and that when said rod 7 is rotated in the opposite direction the sleeves will be moved away from each other to open said inlets.

The means for simultaneously rotating all the rods 7 of the different suction-passages 2 preferably consists of an annular rack 13, the internal teeth 14 of which are adapted to mesh with a plurality of pinions 15, each of which is rigidly mounted on one of the threaded rods 7, so that by rotating the rack 13 with respect to the roll or suction-box 1 the rods 7 will be simultaneously rotated to adjust the sleeves 6. The annular rack 13 is provided with an annular flange 16, which fits into a suitable annular groove in the pe-

periphery of the suction-box 1 and is provided with a set-screw 17, the inner end of which is adapted to contact with the periphery of the box 1. By loosening the set-screw 17 and using the same as a handle the annular rack 13 can be rotated upon the periphery of the suction-box 1 for adjusting the sleeves 6 as described, after which, by tightening the set-screw 17, said sleeves 6 can be locked securely in adjusted position.

For the purpose of holding the annular rack 13 in proper position upon the end of the suction-box 1 a metallic ring 18 is held against the end of the suction-box by means such as the screws 19. The metallic ring 18 is formed with a plurality of openings 20, each of which registers with one of the suction-passages 2.

For the purpose of applying suction to each of the suction-passages 2 when it reaches a certain point in the rotation of the box 1 an end plate 21, such as illustrated in Fig. 6, is placed against each end of the suction-box 1. Each of the end plates 21 preferably is slightly more than semicircular in shape and is provided with an outwardly-extending segmental suction-chamber 22, the inner end of which is open, so as to be adapted to communicate with several of the suction-passages 2, it being understood that each of the end plates 21 is held stationary in any suitable manner, so that as the suction-box 1 is rotated the suction-passages 2 will successively move across the open inner end of the suction-chamber 22. In order that each end plate 21 may be held stationary, the same is provided with a sleeve or tubular extension 23, which loosely surrounds the trunnion or shaft 24 of the roll. The tubular extension 23 may be held stationary in any suitable manner during the rotation of the trunnion 24 and roll or box 1. The suction exerted upon the suction-chambers 22 at opposite ends of the box 1 serves to draw air inward through the inlets 3 and suction-passages 2 as said passages register with said suction-chambers during the rotation of the roll.

For the purpose of cutting off some of the suction-passages 2, so that each suction-chamber 22 will be permitted to register with only one suction-passage at one time, each of the end plates 21 is formed in its inner face, as shown in Fig. 6, with a pair of curved grooves 25, in each of which is mounted a curved or segmental cut-off plate or valve 26, as shown in Fig. 7. Each of the cut-off valves 26 is provided with a set-screw 27, as shown in Fig. 5, extending outward through a curved slot 28, formed in the end plate 21. By loosening the set-screw 27 the cut-off valves 26 can be slid around in the grooves 25, so that their adjoining ends will move partially across the inner open end of the suction-chamber, and thus cut off some of the suction-passages 2, so that, for example, only

one of said suction-passages will be in communication with the suction-chamber 22 at one time. By moving the plates 26 until they contact with each other one of the suction-chambers 22 can be entirely cut off from communication with the suction-passages 2, so as to leave the suction-chamber at the opposite end of the roll 1 to perform the necessary work. Each of the suction-chambers 22 is formed in its peripheral face with an elongated opening 29. Adjustably fitted against the peripheral face of each suction-chamber is a curved plate 30, having an internally-threaded sleeve 31, into which is fitted a pipe-section 32, with which is connected a flexible suction-pipe 33, adapted to be connected with any suitable exhaust-pump or the like. For the purpose of permitting the curved plate 30 to be adjusted upon the suction-chamber 22 so as to regulate the position of the suction-pipe 33, said plate 30 is formed at its opposite ends with longitudinal slots 34, through which extend set-screws 35. By loosening the set-screws 35 the plate 30 can be properly adjusted upon the suction-chamber.

The advantages of the present form of suction-box are that, in view of the fact that the annular rack 13 for adjusting the sleeves 6 is located upon the periphery of the suction-box, two suction-chambers 22 can be employed, one at each end of the suction-box, without interfering with the mechanism for adjusting the sleeves 6. In this way a stronger suction can be secured in the suction-passages 2, and the same can be more evenly distributed.

The improved suction-box of this invention is strong, simple, durable, and inexpensive in construction, as well as thoroughly efficient in operation.

What is claimed is—

1. A suction-box having a plurality of suction-passages having inlets, a suction-chamber at each end of said suction-box, and means located on the periphery of said suction-box for simultaneously shutting off inlets in the several suction-passages.

2. A suction-box having a plurality of suction-passages, a suction-chamber adapted to register with a plurality of said suction-passages, and cut-off valves for regulating the number of suction-passages which shall register with said suction-chamber.

3. A suction-box having a plurality of suction-passages, a suction-chamber adapted to register with a plurality of said suction-passages, and a suction-pipe adjustably connected with said suction-chamber.

4. A suction-box having a plurality of suction-passages formed with inlets, a pair of oppositely-movable sleeves mounted in each of said passages for shutting off some of said inlets, threaded rods for moving said sleeves in opposite directions, pins on said threaded

rods, and an annular rack mounted on the periphery of said suction-box and engaging said pinions for adjusting said sleeves.

5. A suction-box having a plurality of suction-passages, stationary end plates having grooves, a suction-chamber connected with each of said stationary end plates, and cut-off valves slidably mounted in said grooves for partially closing said suction-chamber.

10. A suction-box having a plurality of suction-passages, a suction-chamber adapted to register with a plurality of said suction-passages, said suction-chamber having an elongated opening, an adjustable plate covering said opening, and a suction-pipe connected with said adjustable plate.

15. A suction-box having a plurality of suction-passages formed with tapering inlets, a pair of oppositely-movable sleeves mounted in each of said suction-passages, a reversely-threaded rod in each of said suction-passages for moving said sleeves, a pinion on each of said reversely-threaded rods, an annular rack fitted around the periphery of said suction-

box and engaging said pinions, a set-screw 25 connected with said annular rack and engaging the periphery of the suction-box for holding said rack stationary, rings connected with the ends of said suction-box and having openings registering with the ends of said 30 suction-passages, stationary end plates having grooves, a suction-chamber connected with each of said stationary end plates, cut-off valves mounted in the grooves of said end plates for partially closing each suction-chamber, a curved plate adjustably connected with each suction-chamber, and a suction-pipe connected with each of said adjustable curved plates and communicating with the interior of the suction-chamber. 35 40

In testimony that I claim the foregoing as my own I have hereto affixed my signature in the presence of two witnesses.

BION B. FARNHAM.
